COMESTIBLE SORTING APPARATUS

Harold W. Bartlett, Berkeley, Calif., assignor to California Packing Corporation, San Francisco, Calif., a corporation of New York

Application June 23, 1951, Serial No. 233,232

12 Claims. (Cl. 209—111)

The present invention relates to improved color sorting apparatus of the character shown and described in applicant's copending patent application, Serial No. 80,865, filed March 11, 1949, now abandoned, for "Color Sorting Arrangement," and assigned to the same assignee as the present invention.

In the aforementioned patent application means are provided for sorting or grading peach halves in accordance with degree of ripeness, i. e., in accordance with different shades or colors of the peach halves. Such apparatus generally includes an endless belt upon which the peach halves are carried first under a photoelectric scanning head for deriving intelligence as to the degree of ripeness, i. e., color shading, and subsequently such peach halves are moved away from the scanning head to a different area from where they are removed from the endless belt into one of a plurality of chutes, depending upon the information obtained as to that particular peach half while under the scanning head. Of necessity, such apparatus must incorporate some time delay or "memory" apparatus, so that the intelligence derived while the peach half is under the scanning head may be utilized at a subsequent later time, i. e., a time required for the peach half to move from the scanning head to the position adjacent the chute into which it is ejected from the belt upon which the peach half travels.

The aforementioned patent application incorporates such time delay or "memory" apparatus in the form of releasable buttons which travel a distance corresponding to the desired time delay. While such apparatus is satisfactory for relatively slow sorting or grading, the present application concerns itself particularly with the provision of improved time delay or "memory" apparatus of this character which allows more speedy and reliable operation.

It is therefore an object of the present invention to provide improved time delay or memory apparatus of this character embodied in comestible sorting apparatus of this type.

Another object of the present invention is to provide improved time delay or memory apparatus which utilizes a movable magnetizable member, such member being magnetized in accordance with the intelligence derived by the photoelectric scanning head, and being used subsequently to remove the comestible from its conveying means into a suitable chute or bin.

Another object of the present invention is to provide an improved system of this character for selectively classifying comestibles in accordance with their degree of ripeness.

Another object of the present invention is to provide an improved color sorting arrangement in which articles to be sorted are moved past a scanning head to derive therefrom intelligence as to their physical character, a characterizing feature of the invention being that a novel magnetic type of time delay mechanism is provided whereby such intelligence is used to deflect such article after

2

it passes an appreciable distance beyond the scanning head.

Another object of the present invention is to provide an improved time delay or memory apparatus of this character particularly applicable to conveyor systems in which articles travel along a conveyor belt to subject such articles to control at predictable spaced points beyond a predetermined point at which intelligence is derived.

Another object of the present invention is to provide an improved control circuit for energizing a time delay or memory circuit of this character.

The features of the present invention which are believed to be novel are set forth with particularity in the appended claims. This invention itself, both as to its organization and manner of operation, together with further objects and advantages thereof, may be best understood by reference to the following description taken in connection with the accompanying drawings in which:

Figure 1 shows a comestible sorting system embodying features of the present invention;

Figure 2 is a view in end elevation of a portion of the apparatus which is shown in schematic form in Figure 1;

Figure 3 is a view taken in the direction indicated by the line 3—3 in Figure 2;

Figure 4 is a view taken in the direction indicated by the line 4—4 in Figure 3.

The comestibles or fruit shown in the form of halved peaches P are fed onto the traveling endless belt 10, which preferably comprises a pair of spaced V-belts, as shown in the aforementioned patent application, and which are preferably black in color. The comestibles on such belt 10 pass under a scanning head which incorporates the light source 40 and photoelectric cells 20 and 21, after which such comestibles are disposed in the receptacle 12 in the event that the fruit is completely ripened. In the event that the fruit is not completely ripened, it is removed from the traveling belt 10 into the receptacles 12A, 12B, 12C, 12D by the corresponding ejecting mechanism 13, 14, 15, 16, depending upon the degree of ripeness. The particular form of ejecting mechanism 13, 14, 15, 16, per se, forms no part of the present invention and may comprise solenoid actuated kickers which actually engage the peach halves, as shown in my aforementioned copending application, and may comprise a plurality of air jets. These mechanisms 13, 14, 15 and 16 are actuated in accordance with energization of the corresponding coils 13A, 14A, 15A and 16A, and the connecting mechanisms between the coils and ejecting mechanism are indicated in schematic form by the dotted lines 13B, 14B, 15B and 16B.

These coils 13A, 14A, 15A and 16A are energized in accordance with intelligence obtained by use of the photocells 20 and 21. The photocells 20 and 21 are connected in a bridge circuit and are connected to produce a differential effect on the control grid of the so-called electrometer tube 24. The amplified output current variations of tube 24 are applied to the control grid of discharge device 25 which is connected as a cathode follower. Depending upon the voltage drop in the cathode return circuit of device 25, one or more of the thyratron type of tubes 26, 27, 28, 29 is fired, to thereby energize a corresponding one of the relays having the actuation windings 30, 31, 32 and 33, respectively. The function of these relays generally is to initiate the firing of a corresponding one of the thyratron tubes 34, 35, 36 and 37. The anode circuits of the tubes 34, 35, 36 and 37 include, respectively, the coils 50, 51, 52, 53. These coils 50, 51, 52 and 53 form an important part of the novel time delay or memory apparatus, an important part of which is shown in greater detail in Figures 2, 3 and 4.

Preferably, this apparatus incorporates two rotating magnetizable discs 54, 55 of paramagnetic material driven synchronously with movement of the endless belt 10. For that purpose, the belt pulley shaft 56 is mechanically coupled to the disc shaft 57 by mechanical connections indicated by the dotted line 58 in Figure 1. The coils 52, 53, when energized, are energized only for a brief period of time and produce a magnetized spot on the corresponding discs 54, 55. These magnetized spots, when moved adjacent corresponding pickup coils 50A, 51A, 52A and 53A, induce a corresponding voltage in the grid circuit associated respectively with tubes 50B, 51B, 52B, 53B to fire the corresponding tube and produce a resulting energization of windings 13A, 14A, 15A and 16A, respectively, for the aforementioned purpose of actuating the mechanisms 13, 14, 15 and 16, respectively, to remove the peach half into the corresponding receptacle 12A, 12B, 12C, 12D.

A detailed description of the circuitry shown in Figure 1 now follows.

The anode of phototube 21 is connected to the cathode of phototube 20, and their junction point is connected to the control grid of tube 24 and to one terminal of the grid resistance 60. The cathode of tube 24 is connected to the tap 61 on the voltage dividing resistance 62, and the other terminal of resistance 60 is connected through the movable tap on potentiometer resistance 64 to the negative terminal of resistance 62. One outside terminal of resistance 64 is grounded. The cathode of tube 24 is bypassed to ground by means of condenser 65, and a similar condenser 66 serves to bypass one terminal of resistance 60 to ground.

Voltage is supplied to the voltage dividing resistance 62 by means of a conventional full-wave rectifier having the general reference numeral 67 which is considered to be a source of direct current. The anode of tube 24 is connected to the control grid of the cathode follower tube 25 and is also connected through resistance 68 to the tap 69 on resistance 62 for the flow of space current through tube 24. The screen grid of tube 24 is connected to ground through resistance 70. The anode and screen grid of tube 25 are both connected to the adjustable tap 71 on resistance 62 and to one terminal of the voltage regulator tube 73, which has its other terminal grounded. In such case, a substantially constant voltage is maintained on the anode of tube 25. Phototube 20 has its anode grounded and the cathode of phototube 21 is connected to the negative terminal of resistance 62, such terminal being likewise connected to one terminal of the voltage regulator tube 74, which has its other terminal grounded.

Tube 25 has its cathode returned to ground through the output load resistance 75, and voltages developed across such resistance 75 are transferred, on the one hand, through resistance 76 to the control grid of the thyratron tube 77 and, on the other hand, through lead 78 to the so-called color adjustment circuit 79. Specifically, lead 78 is connected to one terminal of the parallel potentiometer resistances 80 and 81. The adjustable tap 80A on resistance 80 is connected through resistance 84 to the control grid of the thyratron tube 26, and the adjustable tap 81A on resistance 81 is connected through resistance 85 to the control grid of thyratron tube 27. The parallel connected resistances 80, 81 are serially connected with the second pair of parallel connected resistances 86, 87 and with the resistance 88 to ground. In other words, it is clear that the voltage drop across the cathode output resistance 75 is applied to a series circuit which includes first the parallel connected resistances 80, 81, second the parallel connected resistances 86, 87, and third the resistance 88.

Fractional parts of such voltage appearing on the taps 80A, 81A, 86A and 87A may then be applied respectively to the control grids of tubes 26, 27, 28 and 29. It is noted that the tap 86A is connected through resistance 90 to the control grid of thyratron tube 28, and that

the tap 87A is connected through resistance 91 to the control grid of thyratron tube 29. Tube 26 has its screen grid connected through resistance 92 to the tap 96 on voltage dividing resistance 62, and the screen grids of tubes 27, 28 and 29 are connected respectively through resistances 93, 94 and 95 to the tap 97 on resistance 62.

The anodes of tubes 26, 27, 28 and 29 are connected respectively to one terminal of relay windings 30, 31, 32 and 33. These relay windings control the operation of single pole double throw switches which, in normal relatively deenergized position, are as shown in Figure 1, wherein the movable arms of such relays interconnect the bottom relay contacts in a series circuit. The movable arms of the relay switches are connected to one terminal of the corresponding relay windings 30, 31, 32 and 33.

The movable switch arm associated with the winding 33 is connected to a source of positive potential derived in the half-wave rectifier circuit 100, which includes the tube 102. It is observed that the center tap of the high voltage secondary winding 104 is grounded, and that the cathode of rectifier tube 102 is connected to one terminal of the potentiometer resistance 105, which has its other terminal returned to ground through the voltage regulating tube 106. The junction point of resistance 105 and tube 106 is connected to one terminal of coil 33 by means of lead 107. Such lead 107 is of positive potential and is connected through the normally closed contacts of relay switch 33A to the relay coil 32, and likewise through the normally closed contacts of relay switch 32A to the relay winding 31, and likewise through the normally closed contacts of relay switch 31A to the relay winding 30. Thus, normally each of the relay windings 30, 31, 32 and 33 is connected to the positive lead 107, thus conditioning the corresponding tubes 26, 27, 28 and 29 for firing when a voltage of suitable intensity is applied to their corresponding control grids.

It is observed that the relay switches 30A, 31A, 32A and 33A serve also to control the firing of corresponding thyratron tubes 34, 35, 36 and 37 by applying voltage to their corresponding grids. The cathodes of each of the tubes 34, 35, 36 and 37 are grounded. The anodes of tubes 34, 35, 36 and 37 are connected respectively through magnetizing coils 50, 51, 52 and 53 to the lead 108 of positive potential, such lead 108 being connected to one terminal of the condenser 109 and to the adjustable tap on resistance 105, the other terminal of condenser 109 being connected to the negative terminal of voltage regulator tube 106. The screen grids of tubes 34, 35, 36 and 37 are each connected through a corresponding voltage dropping resistance and through lead 113 through the common decoupling and voltage dropping resistance 110 to a tap on the voltage dividing resistance 62. The control grids of tubes 34, 35, 36 and 37 are each connected through corresponding grid resistances to the lead 111, which in turn is connected to the adjustable tap 112 on the voltage dividing resistance 62. Also, the control grid of tube 34 is connected through resistance 34A to the upper terminal of switch 30A; the control grid of tube 35 is connected through resistance 35A to the upper terminal of relay switch 31A; the control grid of tube 36 is connected through resistance 36A to the upper terminal of relay switch 32A; and the control grid of tube 37 is connected through resistance 37A to the upper terminal of relay switch 33A.

The control thyratron tube 77 has its cathode grounded, its screen grid connected through resistance 77A to the tap 96, and its anode connected through the control relay winding 77B to one terminal of the secondary winding 104, so that the anode of tube 77 is supplied with alternating current. Relay winding 77B controls the operation of the normally closed relay switch 77C, which normally grounds the screen grid lead 113 through resistance 114.

The operation of the circuit described above in detail is generally as follows. The thyratron tubes 26, 27, 28 and 29 are normally in condition for firing, since direct

current is applied to their anodes through switches 30A, 31A, 32A, 33A, respectively. Thus, when any one of these tubes fires it will continue to conduct until its corresponding anode voltage is reduced to 11 volts or lower. The control thyratron 77 has alternating current applied to its anode, and hence conducts only when the voltage applied to its grid exceeds a predetermined positive threshold value. The thyratrons used are of the shield or screen grid type. By making the shield or screen grid more negative, a higher positive potential is required on the corresponding control grid to fire the tube.

As explained previously, when a green peach half P is being viewed with light from light source 40, the bias on tube 25 is reduced, causing it to conduct, it being noted that normally in the absence of a peach half the tube 25 is biased in a non-conducting condition due to the biasing lamp 40. This causes a positive voltage with respect to ground to be developed on the cathode of tube 25. Since the control grid of tube 77 is connected to the cathode of tube 25, the tube 77 fires when a relatively small positive voltage appears on its control grid (assuming that the positive half of the alternating current voltage wave is present on the anode of tube 77). When tube 77 fires, relay winding 77B is energized, thereby disconnecting one terminal of resistance 114 from ground and imposing a relatively high negative potential on the screen or shield grids of tubes 34, 35, 36 and 37 through resistance 110, thereby placing such tubes 34, 35, 36 and 37 in a non-firing condition. The control grids of tubes 26, 27, 28 and 29 are biased differently so that they fire at different values of voltage appearing on the cathode load resistance 75. When the voltage on the cathode of tube 25 is progressively raised, the tube 77 is first conditioned to fire, then the tubes 26, 27, 28 and 29 in succession, and in that order, are conditioned for firing. It is observed that when tubes 26, 27, 28 and 29 are fired, the corresponding relay windings 30, 31, 32 and 33 are energized, thereby disconnecting the voltage supply to others. Thus, when the voltage on the cathode of tube 25 is sufficient to condition tube 28 for firing, the anode voltage supplied to tubes 26 and 27 is disconnected and only tube 28 under such condition is fired, it being assumed that the voltage on the cathode of tube 25 is insufficient at this time to cause tube 29 to fire.

It is observed that the tubes 34, 35, 36, 37 have a very high negative bias on their shield grids, and a heavy negative bias on their control grids when the tube 77 is being fired, i. e., when relay winding 77B is energized. Thus, when tubes 77 and 26 fire, the tube 34 does not conduct, even though there is a positive voltage applied to the grid of tube 34 through the normally open contact of relay switch 30A. However, as soon as the peach half leaves the scanning head the biasing lamp 40 causes the tube 25 to become non-conducting and the voltage in the cathode of tube 25 becomes zero, and the control tube 77 is cut off. This allows relay winding 77B to become deenergized and allowing closure of switch 77C. This causes the voltage on the screen grid of tube 34 to increase, so that the tube may be fired in response to the positive voltage applied to its control grid through resistance 34A. It should be noted that at this stage the tube 77 is rendered non-conductive because of the alternating voltage applied to the anode of tube 77, while tube 26 remains conducting since a continuous potential is being applied to its anode and of course at this stage tube 34 is conditioned for firing.

It should be carefully noted that the precharged condenser 109 is used to fire the tube 34, and once the tube 34 is thus fired, the condenser 109 discharges to decrease the potential on lead 108 a sufficient amount to prevent firing. After condenser 109 is thus discharged in accordance with firing of tube 34, the voltage on lead 107 is reduced sufficiently to cause tube 26 to cease firing, especially since at this time, when the peach half has left the

scanning head, the voltage on the control grid of tube 26 is relatively highly negative in nature. Then, as soon as tube 26 ceases to conduct, i. e., ceases firing, its associated relay winding 30 is deenergized, thus in turn allowing the bias on tube 34 to become highly negative to an extent that it will not conduct until the next cycle.

From the foregoing description of the operation, it is evident that short pulses of energy are supplied to the magnetizing coils 50, 51, 52 and 53, depending upon the relative magnitude of the voltage developed on the cathode of tube 25, i. e., in accordance with the degree of ripeness of peach half P. Such short pulses of energy are used to produce magnetized spots on hardened steel discs 54, 55 (Figures 1 and 2) running in synchronism with the endless belt 10 upon which the peach halves are transported. Assuming as before that the pulse of energy is delivered to the coil 50, a magnetized spot appears on the disc 54. Then, when the disc travels in its orbital path adjacent the corresponding pickup coil 50A of relatively large number of turns, a corresponding voltage is induced in the coil 50A, and such voltage is applied to the control grid of the thyratron tube 53B to fire the same. Similarly, the coil 51A is connected to the control grid of tube 52B, the pickup coil 52A is connected to the control grid of tube 51B, and the pickup coil 53A is connected to the control grid of tube 50B. The control grids of these tubes are normally biased negatively by small direct current voltage sources, and the anode of each is supplied with alternating current from the alternating current source 120, which has one of its terminals connected to the cathodes of tubes 50B, 51B, 52B and 53B and the other one of its terminals connected to the corresponding anodes through solenoid or relay windings 13A, 14A, 15A, 16A. Energization of any one of these windings 13A, 14A, 15A, 16A results in operation of the corresponding peach half ejecting mechanism 13, 14, 15, 16, which mechanism operates to deflect or move the peach halves laterally from the belt 10 into corresponding receptacles 12A, 12B, 12C and 12D, all in accordance with the degree of ripeness of the peach halves.

Referring to the specific structures shown in Figures 2, 3 and 4, the coils 50 and 51 are mounted on stationary bracket members 121, 122, respectively, on the stationary support 12. The coils 50 and 51 comprise a plurality of wire turns around one of the legs of corresponding yokes 125, 126, the other legs of such yokes 125, 126 being disposed adjacent the magnetizable discs 131, 132, respectively, between which the disc 54 is sandwiched.

It is observed that the magnetic axes of the coils 50, 51 are disposed at different radial distances from the center of rotation of disc 54, i. e., the axis of shaft 54 upon which the disc 54 is mounted, so that the magnetized spots produced by the coils 50 and 51 extend a greater and a shorter distance, respectively, from the rotational axis of the disc. The pickup coil 50A is spaced circumferentially from the corresponding magnetizing coil 50, but at the same radial distance from the axis of rotation, whereby the spot magnetized by the coil 50 passes adjacent the magnetic axis of the coil 50A. Similarly, the spot of magnetized material produced by coil 51 passes immediately adjacent the magnetic axis of the pickup coil 51A. It is observed that the yokes for each corresponding magnetizing and pickup coil are essentially the same and serve to establish a magnetic path which passes through such yokes, the disc 54, as well as the magnetizable discs 131, 132.

Preferably, the pickup coils 50A and 51A are adjustable along the circumference of the disc 54 to correspond exactly with the distance between, on the one hand, the scanning head where intelligence is derived by means of the photocells 20, 21 and, on the other hand, the ejecting mechanisms 13, 14, 15, 16, as the case may be. For this purpose, the rotatable disc shaft 57 floatingly supports the collars 135, 136, each of which mounts a worm gear 137, 138, cooperating respectively with the manually

operable worm 139, 140. A suitable collar 141 may be mounted directly to the shaft 57 to prevent movement of the collars or sleeves 135, 136 along the longitudinal axis of the shaft. The worm gear 140, as shown in Figure 3, may have its shaft 142 journaled for rotation on the stationary frame member 143 which carries indicia 144 readable in relationship to the position of the pointer 145 mounted on the shaft 142, to allow the operator to determine visually the relative position of the pickup coil 51A. Similar adjusting and indicating means are provided as shown in Figure 2 for the other pickup coil 50A.

The disc 54 is rotated in the counterclockwise direction as indicated by the arrow 147 in Figure 3 for movement adjacent the stationary Alnico magnet 150 (Figures 3 and 4), such magnet 150 being provided for erasing purposes. In other words, the magnetized spots produced by the coils 50, 51, after producing their effects in the pickup coils 50A, 51A, are moved adjacent the legs of the Alnico magnet 150 which serves to erase such spots.

It is observed that the Alnico magnet 150 has a north pole and a south pole, as indicated by the letters "N" and "S" in Figure 4, and such poles are spaced a distance corresponding to the radial spacing between the magnetic axes of the coils 50 and 51. It is noted that the coils 50, 51 are polarized differently so that the north and south poles of the magnet 150 are effective to provide erasure. It should be observed that the pickup coils 50A and 51A also have different polarities and are sensitive to either a north or a south polarity, as the case may be. By this expedient "cross-talk" effects between the two different magnetized spots produced by the coils 50 and 51 are avoided. In other words, unless the voltage developed in the pickup coils 50A and 51A produces a positive voltage on the grids of corresponding tubes 50B, 51B, the corresponding windings 13A, 14A are not energized.

While the particular embodiments of the present invention have been shown and described, it will be obvious to those skilled in the art that changes and modifications may be made without departing from this invention in its broader aspects and, therefore, the aim in the appended claims is to cover all such changes and modifications as fall within the true spirit and scope of this invention.

I claim:

1. In apparatus of the character described, means effective to derive a control voltage varying in magnitude in accordance with the color of comestibles, a rotatable magnetizable disc, a plurality of magnetizing windings magnetically associated with said disc, a corresponding plurality of pickup coils magnetically associated with said disc, means selectively energizing only one of said plurality of magnetizing windings in accordance with the particular magnitude of said voltage, and means including said pickup coils for effecting control operations on said comestibles.

2. In apparatus of the character described, conveying means, a magnetizable disc operated synchronously with said conveying means, first means deriving a voltage in accordance with physical characteristics of nonmagnetizable articles on said conveying means, a plurality of magnetizing windings magnetically associated with said disc, a plurality of corresponding pickup coils magnetically associated with said disc, means deriving and applying energy pulses to corresponding selected ones only of said plurality of magnetizing windings in accordance with particular said voltage derived by said first means, and means including said plurality of pickup coils for effecting control operations on said articles.

3. In apparatus of the character described, conveying means, a magnetizable member operated synchronously with said conveying means, first means deriving a voltage in accordance with physical characteristics of nonmagnetizable articles on said conveying means, a plurality of magnetizing windings magnetically associated with said member, a plurality of corresponding pickup means magnetically associated with said member, means deriving

and applying energy pulses to a selected corresponding one only of said plurality of magnetizing windings in accordance with said voltage derived by said first means, and means including said plurality of pickup means for effecting control operations on said articles.

4. In an arrangement of the character described, article conveying means, means at a point of selection for deriving intelligence as to the physical characteristics of nonmagnetizable articles on said conveying means, said intelligence deriving means including means for deriving a voltage, the magnitude of which is representative of the physical characteristics of said articles, a magnetizable member synchronously operated with said conveying means, a plurality of magnetizing means magnetically associated with said magnetizable member, means selectively coupling a corresponding one only of said plurality of means to said voltage deriving means in accordance with the particular magnitude of said voltage, said coupling means incorporating means whereby only one of said plurality of means is energized at a particular time, a corresponding plurality of pickup means magnetically associated with said magnetizable member, and control means coupled to said pickup means for effecting control operations on said articles remote from said point of selection.

5. In an arrangement of the character described, article conveying means, means at a point of selection for deriving a voltage varying in intensity in accordance with physical characteristics of nonmagnetizable articles on said conveying means, a magnetizable member synchronously operated with said conveying means, a plurality of magnetizing means magnetically associated with said magnetizable member to magnetize regions in the same, selectively and automatically operative means responsive to the particular intensity of said voltage for energizing a corresponding one only of said magnetizing means, and control means operated in accordance with magnetization of said magnetizable member for effecting control operations on said articles remote from said point of selection.

6. In an arrangement of the character described, article conveying means, means at a point of selection for deriving a voltage varying in intensity in accordance with physical characteristics of nonmagnetizable articles on said conveying means, a magnetizable member synchronously operated with said conveying means, a plurality of magnetizing means magnetically associated with said magnetizable member to magnetize the same, selectively and automatically operative means responsive to the particular intensity of said voltage for energizing a corresponding one of said magnetizing means, and control means operated in accordance with magnetization of said magnetizable member for effecting control operations on said articles, said control means comprising a plurality of pickup coils magnetically associated with said magnetizable member and each corresponding to one of said magnetizing means.

7. In an arrangement of the character described, photo responsive means for developing a voltage varying in accordance with physical characteristics of articles, a first gaseous control tube coupled to said photo responsive means and operated in accordance with said voltage, said gaseous control tube having an anode, a first control relay with a winding, an alternating current voltage source connected to said anode through said first control relay winding, a second gaseous tube coupled to said photo responsive means and operated in accordance with said voltage, a continuous voltage source, a second control relay with a winding, a resistance, means connecting said continuous voltage source to the anode of said second tube through said second control relay winding and said resistance to provide a discharge path for said second tube, a third gaseous tube having an anode, a magnetizing coil, a condenser, means coupling said condenser to said continuous voltage source through said resistance, said condenser being serially connected with said coil to the anode of said third tube, means including said first control relay

for rendering said third tube inoperative, means including said second control relay for rendering said third tube operative to discharge said condenser through said coil, and means including said resistance for rendering said second tube inoperative in accordance with discharging of said condenser.

8. In an arrangement of the character described, photo responsive means for developing a voltage which varies in accordance with physical characteristics of a non-magnetizable article, a plurality of magnetizing means, a plurality of gaseous discharge tubes, each having its anode serially connected with a corresponding one of said magnetizing means, a single condenser serially connected with each of said magnetizing means and corresponding anodes and corresponding tube cathodes, a continuous voltage source, a resistance serially connected with said source, a charging circuit for said condenser comprising said resistance and said source, a second plurality of discharge tubes each effective to energize a corresponding one of said first plurality of tubes in accordance with the magnitude of said voltage, each of said second plurality of tubes being energized by said source through said resistance, and a control tube operated in accordance with the magnitude of said voltage for deenergizing each of said first plurality of tubes.

9. In an arrangement of the character described, article conveying means, means at a point of selection for deriving a voltage which varies in accordance with physical characteristics of articles on said conveying means, a magnetizable member synchronously operated with said conveying means, a plurality of magnetizing means magnetically associated with said magnetizable member to magnetize different regions in the same, a first plurality of gaseous discharge tubes each having its anode serially connected with a corresponding one of said magnetizing means, a single condenser serially connected with each of said magnetizing means and corresponding anodes and corresponding tube cathodes to provide a discharge path for said condenser, a continuous voltage source, a resistance serially connected with said source, a charging circuit for said condenser comprising said resistance and said source, a second plurality of discharge tubes each effective to energize a corresponding one of said first plurality of tubes in accordance with the magnitude of said voltage, each of said second plurality of tubes being energized through said resistance, a control tube operated in accordance with said voltage for deenergizing each of said first plurality of tubes, a plurality of pickup means magnetically associated with said magnetizable member and each corresponding to a corresponding one of said magnetizing means, and control means coupled to said pickup means for effecting control operations on said articles remote from said point of selection.

10. In an arrangement of the character described, article conveying means, means at a point of selection for deriving voltages varying in accordance with physical characteristics of articles on said conveying means, a magnetizable member synchronously operated with said conveying means, a plurality of magnetizing means magnetically associated with said magnetizable member to magnetize selected regions in the same, a first gaseous control tube coupled to said voltage deriving means and operated in accordance with said voltage, said gaseous control tube having an anode, a first control relay with a winding, an alternating current voltage source connected to said anode through said first control relay winding, a first plurality of gaseous discharge tubes, each coupled to said voltage deriving means and operated differently in accordance with the magnitude of said voltage, a continuous voltage source, each of said plurality of tubes having a corresponding control relay with a winding, a resistance, means connecting said continuous voltage source to the anodes of each of said plurality of tubes through corresponding control

5 relay windings and through said resistance to provide a common path for the flow of space current through each of said plurality of tubes, a second plurality of gaseous tubes each having an anode, a condenser, means coupling said condenser to said continuous voltage source through said resistance to form a charging circuit for said condenser, the anodes of each of said second plurality of tubes being serially connected with a corresponding one of said plurality of magnetizing means, said condenser being serially connected with each of said magnetizing means and corresponding anodes of said second plurality of tubes, means including said first control relay for rendering each of said second plurality of tubes inoperative, means including said corresponding control relays for rendering a corresponding one of said second plurality of tubes operative to discharge said condenser through a corresponding magnetizing means, pickup means magnetically associated with said magnetizable member with each pickup means corresponding to one of said magnetizing means, and control means coupled to said pickup means for effecting control operations on said articles remote from said point of selection.

11. In an arrangement of the character described, a magnetizable member rotatable about an axis, a plurality of magnetizing coils each being mounted at different radial distances from said axis and magnetically associated with said member, a plurality of gaseous discharge devices each having an output electrode connected to a corresponding one of said coils, means at a point of selection 25 for deriving an electrical voltage, the magnitude of which is representative of the condition of a non-magnetizable article at such point of selection, means for conditioning one of said devices for firing in accordance with the magnitude of said electrical voltage, means assuring a non-conductive condition of the selected device when said article is at said point of selection, the last mentioned means being automatically disabled when said article leaves said point of selection to thereby allow the selected discharge device to allow a current flow from its output electrode and through the corresponding magnetizing coil.

12. In an arrangement of the character described, a magnetizable member rotatable about an axis, a plurality of magnetizing coils each being mounted at different radial distances from said axis and magnetically associated 45 with said member for producing a corresponding magnetized spot on said magnetizable member, a plurality of pick-off coils magnetically associated with said magnetizable member, article diverting means, a plurality of gaseous discharge devices each coupled to a corresponding pick-off coil, said article diverting means comprising means controlled directly by a flow of space current through the corresponding discharge device, each of said pick-off coils being effective when a magnetizable spot moves adjacent the same to fire a corresponding one of 50 said devices, and means automatically effective after said spot passes the corresponding pick-off coil for restoring the corresponding discharge device to a non-conducting condition.
